Wm. H. Ames

BY Francis M. Wright.
ATTORNEY

UNITED STATES PATENT OFFICE.

WILLIAM H. AMES, OF WATSONVILLE, CALIFORNIA.

REFRIGERATOR-CASE.

SPECIFICATION forming part of Letters Patent No. 700,721, dated May 27, 1902.

Application filed July 5, 1901. Serial No. 67,205. (No model.)

To all whom it may concern:

Be it known that I, WILLIAM H. AMES, a citizen of the United States, residing at Watsonville, in the county of Santa Cruz and State 5 of California, have invented certain new and useful Improvements in Refrigerator-Cases, of which the following is a specification.

My invention relates to improvements in refrigerator-cases, the object of my invention 10 being to provide a device of this character by means of which perishable fruits can be stored and shipped to a distant point and preserved in the same case for a considerable time at a sufficiently-cold temperature to prevent the 15 fruit spoiling, not only during transit, but after arriving at its destination and when on sale by the retailer until the whole of the fruit has been sold. The case, in which the 20 fruit has been preserved up to the moment of sale, is then returned to the shipper.

A further object of the invention is to provide means for preventing the jarring and 25 jolting of the fruits or berries against each other, which is one of the principal causes of the spoiling of perishable fruits in traveling long distances.

The object of my invention is to simplify 30 the construction of such refrigerator-cases, rendering it easier to keep the same supplied 35 with ice and also cheaper and simpler to construct.

My invention therefore resides in the novel 40 construction, combination, and arrangement of parts for the above ends hereinafter fully 45 specified, and particularly pointed out in the 50 claims.

In the accompanying drawings, Figure 1 is 55 a vertical section of the refrigerator-case, taken on the line A A of Fig. 2, parts being 60 broken away. Fig. 2 is a similar section taken on the line B B of Fig. 1. Fig. 3 is a 65 broken perspective view of one of the uprights for the rails carrying the trays. Fig. 4 is a side view of the same, partly in vertical 70 sections. Fig. 5 is a detail of one of the 75 hangers for the rails. Fig. 6 is a side view 80 of the trap. Fig. 7 is a vertical section of 85 the same, and Fig. 8 is a side view of the support for the trough. Fig. 9 is a side view 90 of the trough.

Referring to the drawings, 1 represents a 95 box or case closed at the top, bottom, sides,

and back and open at the front. A door 2 is provided for closing the front, which door may be either single or double, as desired.

3 is an ice-receptacle suitably supported in 55 the top of the case, having a wooden body 4 and a metallic lining 5. Within said receptacle the blocks of ice are deposited upon a grating comprising lower transverse strips 6 and upper longitudinal strips 7 laid across 60 the transverse strips. Through this grating the water into which the ice in the receptacle melts flows and discharges by an elongated spout 8 into a trough 9, from which trough the water passes, by means of a pipe 65 10 at the front end of the trough, into the rear end of a trap 11, said trap comprising a casting having vertical partitions 12, extending from the bottom and top, respectively, to within a short distance of the top and bottom. 70 A pipe 13 leads from the front end of said trap to the exterior of the case. By this means the water of the melting ice is discharged outside the case, while the hot air from outside is prevented by the trap from 75 entering the refrigerator-case. Also it will be seen that by this construction a large clear space is provided in the receptacle for receiving the blocks of ice.

An important feature of my invention re- 80 sides in the provision which I have made for preventing shaking of the fruits or berries with each other, and for this purpose I provide at each side of the case and also in the middle pairs of uprights or supports 14, which 85 rest upon springs 15 and slide in guides 16. The guides 16 at the sides of the case are secured to said sides, while in the middle said guides 16 are secured to the uprights 17 of the frame or support 17 for the trough 9. 90 From the supports 14 rails 18 are suspended by means of hangers 19, made of wire bent into a hook shape, as shown, the oblique bent ends of said hangers entering oblique holes 20, formed in the supports 14. Two such se- 95 ries of holes 20 are formed, the holes or sockets of one series being spaced at different intervals from each other from those of the other series, as shown in Fig. 3, thus permitting the rails 18 to be adjusted according to 100 the size of the boxes. Said boxes rest upon trays or shelves 21 sliding on said rails.

With this construction it will be seen that the cold air passes downward through the spout 8, over the edge of the trough 9, then down the refrigerator-case at the center. 5 The air rises at both sides, being the warmest. Thus an excellent circulation is produced, and the refrigerator-case is thus one of great efficiency.

10 I do not confine my invention to the particular form and arrangement of springs used for sustaining the supports, as other forms of springs may be used and in other ways for accomplishing the same result.

I claim—

15 1. In a refrigerator-case, the combination with upright supports having a plurality of series of sockets, the sockets of one series being spaced at different intervals from those of another series, of hangers having one end 20 removably inserted in said sockets, rails through which the other ends of the hangers

pass to support the same, and trays sliding on said rails, substantially as described.

2. In a refrigerator-case, the combination of supports having downwardly-inclined 25 sockets, wire hangers having downwardly-bent portions in said sockets, rails in which the other ends of said hangers are inserted, and trays sliding on said rails, substantially as described. 30

3. In a refrigerator-case, the combination of trays, vertical supports thereof, guides in which said supports slide, and springs for resiliently sustaining said supports, substantially as described. 35

In witness whereof I have hereunto set my hand in the presence of two subscribing witnesses.

WILLIAM H. AMES.
